UNITED STATES PATENT OFFICE

WILLIAM EDISON BAIR, JR., OF CHILlicothe, OHIO, ASSIGNOR TO THE MEAD CORPORATION, OF DAYTON, OHIO, A CORPORATION OF OHIO

PAPER MANUFACTURE

Application filed March 9, 1931. Serial No. 521,118.

This invention relates to the manufacture of paper; and one of the principal objects of the invention is to provide a method of forming paper which includes effecting controlled 5 formation as to the opposite sides to produce a formed sheet or web of paper of hitherto unknown and superior characteristics.

Another object of the invention is to provide such a method in the formation of a 10 paper sheet which produces paper free from "two-sidedness".

Still another object is to provide as a superior product a paper formed with controlled body and surface characteristics.

15) Another object of the invention is to provide apparatus for carrying out this method and producing such a product, which is simple in construction and effective in operation.

Other objects and advantages of the invention will be apparent from the description 20 thereof set out below and from the accompanying drawing and from the claims.

As is well known, in the manufacture of paper it is the general practice to bring the 25 paper forming stock onto a forming wire,—such as the traveling wire of a Fourdrinier machine,—through which the water may pass leaving a web or sheet of matted fibers upon the wire. The stock constituency varies according to the operating circumstances 30 and the end product desired, and comprises pulp made from the properly separated fibers of wood, or the like suspended in water, with admixed filler, size etc. It is a very general 35 practice, particularly where paper of a better grade is to be made,—such for example as is used for book or magazine printing,—to admix with the fibrous suspension a considerable proportion of finely divided clay or other 40 filler, size or other constituents; the materials and the proportions thereof used varying somewhat according to the character of sheet desired. While the stock is on the forming wire some of the water escapes through the 45 wire, the fibers remaining to form the web or sheet of paper which is subsequently removed from the wire and subjected to additional treatment, such as pressing, drying, calendering, coating, and the like.

50) With particular reference to a Fourdrinier

machine, which type is illustrated in the drawing for purposes of description, as the stock is flowed onto the wire there is quite a rush of water through the wire during the first few feet of travel of the stock upon the wire, and some of the finely divided filler and other finely divided constituents, and some of the finer fibers, tend to flow away with the water through the forming wire. A large part of so much of the water of the stock as 55 ultimately escapes through the forming wire 60 before the formed web is removed therefrom, escapes before the suction boxes are reached, partly under the action of gravity and partly 65 due to the action of the table rolls. The remainder of the water which is removed before the forming web is taken from the wire is removed during the remaining distance of travel of the wire, particularly while it is 70 passing over the suction boxes and while it is 75 passing over a suction couch roll, if such is used. As the stock flows onto the wire the greater portion of the fibers are stopped by the wire and matted thereon forming a filtering mat or web through which the remainder 80 of the water passes or is drawn to escape through the wire side. The table rolls as they revolve carry around a film of the escaping water which tends to further wash out 85 filler and other finer materials. Also at the 80 suction boxes the suction tends to withdraw some of the filler, etc. with the removed water; and the same thing is true at the suction couch roll. A paper sheet as heretofore so formed ordinarily has different surface characteristics on its opposite sides. The wire 90 side differs from the opposite or upper side both in texture and appearance; this condition of different surface characteristics being known in the industry as "two-sidedness". 95 In the formation of the sheet, with all of the water being drawn downwardly or through the sheet in one direction to escape through the wire, there results a non-homogeneous distribution of the filler, and of the fiber also, 95 within the sheet. As a result the fibers of the upper side are generally finer than those on the wire side giving different textures and appearances to the opposite sides. Also the relative quantity of retained filler, etc. de- 100

creases from the top side to the wire side, which may have substantially no retained 5 filler. This lack of homogeneity, and the exaggerating of it which attends in progressing degree upon the use of increased quantities of filler, is universally recognized in the industry as is also the fact that the practicable limit of differentiation in the two sides definitely limited the proportion of filler that 10 might be contained in a sheet. That is, if the two-sidedness becomes too marked the sheet has no marketability and utility,—or, at least, its marketability and commercial 15 value are seriously decreased, even if not destroyed. This is especially true with book paper, such as is used for magazines and the like. It has heretofore been ordinarily considered commercially impracticable to provide as much as 25% of filler on the dry 20 weight of the fiber, in the finished sheet, and still secure paper suitably usable on the score of two-sidedness. Even with 20% of filler it has been very difficult to maintain the wire side and the opposite side of sufficiently similar 25 surface characteristics. However, from a practical point of view additional quantities of filler are very desirable, for it may be generally said that the printing qualities of a sheet of paper improve as the quantity of 30 filler carried at the surface increases. Also, as the filler is probably the cheapest ingredient going into the stock, from a commercial point of view it is desirable to minimize the amount of pulp,—using so much fibrous material 35 as is necessary for giving sufficient strength to the desired paper web, with added inclusion of filler to add body, opacity and printing quality. The present invention permits of forming a sheet of paper under such 40 conditions as to produce new surface characteristics with the wire side approximating the top side characteristics. This permits of forming a sheet having a quantity of filler equal to or even greatly increased over those 45 quantities heretofore considered practicable, but with the sheet still quite free from the objectionable two-sidedness heretofore experienced.

For purposes of description, and as setting 50 out a form of mechanism which will operate in a very satisfactory manner for the carrying on of the method of this invention and the producing of the new paper product, a conventional form of Fourdrinier paper making machine is illustrated in the drawing, 55 largely in diagrammatic form. In the drawing the numeral 10 designates generally the frame of the wire section of the paper making machine, which frame carries the usual forming wire 11 supported by a breast roll 13, and a couch roll 14 preferably of the suction couch type. Any suitable stock supplying 60 inlet or means may be utilized, such means being shown diagrammatically and designated by the numeral 15. The numeral 16

designates the dandy roll just beyond which are located the suction boxes 17. Located between the suction couch roll 14 and the suction boxes 17 is the wire guide roll 20.

In accordance with the present invention 70 additional forming material is applied to the wire side of the paper, after it has arrived at a sufficiently definite stage of formation. When filler suspension is applied under such conditions of dryness of the web that the 75 liquid of the forming material suspension is readily absorbed by the wire side of the sheet it will carry the filler, etc. into the interstices,—into the body of the sheet,—, where it will be deposited and retained, some being 80 also retained in and on the fibers at the surface of the web. In the type of machine shown in the drawing this definite or initial stage of formation is ordinarily reached during the passage of the forming sheet or web 85 over the suction boxes, and the condition is indicated by the web losing the liquid appearance which it has up to that stage. When the forming paper web moves up to the regular suction box zone it gives the appearance of 90 a pool or sheet of water suspension, but as the wire moves along the watery sheen or glitter disappears as more water is removed, until the sheet as it assumes its initial definite 95 form has the appearance of a damp or moderately wet sheet of paper. This change usually occurs as the web passes over the suction box zone, but whatever the precise moment of its occurrence it is an easily recognized change. In actual commercial use of 100 the invention it was found that as the initially formed sheet moved away from the last suction box it contained from 14 to 19% of solids—or 81 to 86% of water. At this stage 105 the sheet, as stated, is sufficiently definite in form and has sufficient water absorption capacity to permit of practising the present invention. Actual commercial practices also show that the above described change in the sheet probably takes place when sufficient water has been removed to leave approximately 110 90% of water and 10% of solids in the forming web.

When the invention is practised with the apparatus shown, the roll 20 causes the added material to be carried up through the wire onto the wire side of the web, as a result of which the filler content will be embodied into the web in a proportion decreasing from the surface inwardly. The depth to which the 115 filler penetrates and its distribution may of course vary somewhat; but it penetrates in decreasing quantity to a considerable distance and without abrupt change or line of cleavage, as would be the case with a layer 120 of coating material applied merely to the sheet surface. By properly proportioning the constituents of the additive material, as to filler, etc. the surface characteristics may be caused to more or less closely approach 125

the characteristics of the other side of the web, as to actual texture, susceptibility to printing, apparent surface characteristics, etc. In addition to deeply penetrating the sheet, the filler is also deposited and held on the surface fibers so as to whiten the wire side and give that side the same appearance as the other side. The effect in this respect is as if the wire side had been whitewashed to bring it up to the same appearance of whiteness as the other side. In actual commercial operations the appearance of the wire side of paper formed according to this invention so closely approaches in characteristics the upper side that there is no evidence of objectionable two-sidedness.

Causing the filler suspension to pass up through the wire and onto the wire side of the web may result in somewhat weakening the finished sheet, but by the addition of suitable amounts of size or bonding agent, this tendency to weakening of the web is avoided and the finished sheet will have as great strength as if it had been formed in the heretofore usual way. No claim is made herein to this, however, since it is an improvement invented by James d'A. Clark and John E. Graves, Serial No. 555,757, filed August 7, 1931.

As shown in the drawing a trough 30 is positioned beneath the wire guide roll 20, which trough is suitably supported upon the frame of the machine, or upon the bearing support for the wire guide roll, or in any other satisfactory way, within which is maintained a supply of suitable surfacing material. As shown the trough is provided with a supply pipe 31 and an overflow 32 so that during operation the height of the filler suspension in the trough is maintained substantially constant, and of sufficient height to partly immerse the lower portion of the roll, and thus give a substantially uniform application to the forming web, under various operating conditions of speed, etc. As the roll rotates it picks up a film thereon which is maintained continuously around the roll, with the wire riding on or through this film and the suspension is thus brought into contact through the wire with the wire side of the web, and is incorporated therein. The paper at this point having lost a considerable portion of the original water content, as stated above, is absorbent and readily receives the water and entrained suspended material so that a firm and homogeneous intermixture and bonding of the new material into the forming sheet, in an amount decreasing inwardly, is secured. In satisfactory practicing of the invention the wire guide roll of the usual diameter of about 10 inches and having a surfacing of hard rubber has been used. As stated above, the web at the wire guide roll shown contains 14 to 19% solids and 86 to 81% water. This particular moisture content is not thought

essential, but the moisture content may be considerably less than that specified. The moisture content after the paper web is removed from the suction couch and as it passes up to the first press, has been found to vary with character of stock, the suction at the couch roll, etc., and in the operation of the commercial machine on which this invention has been practiced, the variation has been from between 75 to 80%, depending on the suction at the couch roll, with some 20-25% or less of solids; and as the invention is now understood it is believed that it may be practiced satisfactorily by applying the additive material to the initially formed web within a proportion range of solid to moisture running from 10% solid and 90% moisture up to about 30% solid and 70% moisture.

If desired the filler suspension may be applied to the wire side of the web by using a slotted pipe, instead of a revolving roll. Also a separate wire or felt may be used for carrying the filler suspension up for application onto the paper web, located, for example, between the suction couch and the first press roll. But no claims to these improvements are included herein since they constitute inventions of James d'A. Clark and John E. Graves, as set forth in their above referred to application, and of James d'A. Clark and John Traquair, as set forth in their application Serial No. 564,790, filed September 24, 1931.

After the added material is applied to the web the processed sheet is subjected to additional suction by the suction couch where water and some of the surfacing material is withdrawn. The roll 20 is operated to supply an excess of suspension material so that a desired amount will be retained in the finished sheet. The paper web is then removed and transferred to a felt 40 which passes it through the several sets of presses 41 in the usual manner; after which it will be passed on through the other parts of the machine where it can receive the ordinary pressing, or such subsequent modified treatment as may be needed to produce the desired final product.

In the forming of paper sheets the stock originally supplied must contain a considerably greater quantity of filler, etc., than will appear in the ultimate product. In actual operations it has been found that to secure a finished sheet having 25% filler about 50% of filler, on the fiber content, should be added to the stock. But without the practising of this invention such proportion of filler in the finished product would give evident and marked two-sidedness. In the practising of this invention the percentage of filler contained in the stock has been increased to about 55%, of which about 27% remains in the finished sheet. Satisfactory results, with substantial elimination of two-sidedness, has been secured where the ma-

aterial within the trough 30 consists of a suspension of a carbonate, or other similarly acting filler in water, containing 22 pounds of carbonate filler and 3½ pounds of size in 5 40 gallons of water. With such suspension the web will receive and retain of the additive material an amount of filler which represents from 1 to 2% of the total weight of the finished sheet. That is, with a sheet be- 10 ing formed from the stock above specified which would give approximately 27% of filler in the finished sheet, by adding the suspension material as described an additional 1 to 2% of filler will be included with the 15 elimination of two-sidedness. The resulting sheet will be satisfactorily improved as to its two-sidedness, even if the size is omitted.

While the process herein described, and the form of apparatus for carrying this process into effect, constitute preferred embodiments of the invention, it is to be understood that the invention is not limited to this precise process and form of apparatus, and that changes may be made in either without departing from the scope of the invention which is defined in the appended claims.

What is claimed is:

1. In the manufacture of paper the method which comprises introducing paper forming stock onto a forming wire, and adding additional paper forming material to the wire side of the forming web, while the web is still upon the forming wire.

2. In the manufacture of paper the method which comprises introducing paper forming stock onto a forming wire, and incorporating additional paper forming material into the wire side of the forming web, before the forming web is withdrawn from the forming wire.

3. In the manufacture of paper the method which comprises adding additional paper forming materials to the web, through the wire, beyond the suction box zone.

4. In the manufacture of paper the method which comprises adding additional paper forming materials to the wire side of the web, in advance of the couch roll.

5. In the manufacture of paper the method which comprises adding paper forming material to the web, by depositing such material on the web through the forming wire.

6. In the manufacture of paper the method which comprises bringing a paper forming stock onto a forming wire and removing water therefrom to effect an initial definite formation of the web, and then bringing a suspension of additive material into absorbing contact with the wire side of said sheet while in its initially formed state.

7. In the manufacture of paper the method which comprises bringing a paper forming stock onto a forming wire and removing water therefrom to effect an initial definite formation of the web, and then bringing a

suspension of additive material into absorbing contact with said sheet through a wire.

8. In the manufacture of paper the method which comprises bringing a paper forming stock onto a forming wire and removing water therefrom to effect an initial definite formation of the web, and then bringing a suspension of additive material into absorbing contact with said sheet through a wire, said additive material comprising a suspen- 7 sion of filler.

9. In the manufacture of paper the method which comprises bringing a paper forming stock onto a forming wire and removing water therefrom, and bringing a suspension 8 of additive material into contact with the wire side of said sheet through said wire when the moisture content has been reduced to 90% or less.

10. In the manufacture of paper the method which comprises introducing a paper forming stock which includes fibrous material, filler and the like, onto a forming wire, withdrawing a portion of the suspension water and entrained fiber, filler and the like through the wire, and adding additional paper forming material to the wire side of the resulting wet web while in its initially formed receptive state to incorporate additional paper forming material 9 into the wire portion of the wet web with the quantity of incorporated materials decreasing in proportion from the wire side of the web inwardly of the web.

11. In the manufacture of paper, to produce a paper of high filler content free from two-sidedness, the method which comprises introducing a paper forming stock which includes fibrous material, filler and the like, onto a forming wire, withdrawing a portion 1 of the suspension water and entrained fiber and the like through the wire, and adding additional paper forming material to the wire side of the resulting web to incorporate additional paper forming material into and on the wire portion of the wet web to effect a whitewashing thereof, the quantity of material thus added being sufficient to bring the color appearance of the wire side up to approximately the color appearance of the opposite side of the web.

12. As a product of manufacture a filled paper containing in excess of 10% of filler, and having the constituent materials thereof so distributed during formation of the web as to produce substantially the same surface characteristics on both sides.

13. As a manufactured product, a filled paper comprising fibrous material and incorporated filler, with the filler decreasing in proportion from each surface inwardly toward the center of the web.

14. As a manufactured product, a filled paper comprising fibrous material and originally incorporated and added filler, with

the added filler decreasing in proportion from the surface inwardly toward the center of the web without abrupt change in the decreasing proportions.

5 15. In the manufacture of paper the method which comprises introducing a paper forming stock onto a forming wire, withdrawing a portion of the suspension water through the wire to effect an initial definite web formation and adding additional forming material to the web while wet in its initially formed receptive state to incorporate additional forming material thereinto.

10 15 In testimony whereof I hereto affix my signature.
